Atty.

UNITED STATES PATENT OFFICE

MARTIN C. DELLINGER, OF LANCASTER, PENNSYLVANIA

SAFETY RAZOR HANDLE

Application filed February 16, 1929. Serial No. 340,613.

This invention relates to safety razors of the hoe type, and more particularly to the handles thereof, and to the combination of such a handle with a styptic pencil.

5 The objects of the invention are to provide in combination a handle and a styptic pencil carried in the handle so as to be immediately at hand and quickly and certainly removable from the handle in case of need; 10 to provide such a combination of said handle and the styptic pencil that the latter will normally be contained in said handle and protected against moisture; to provide in such combination a plug for closing the open 15 end of the handle, said plug serving as a convenient mount and grip for the styptic pencil, and to provide means preventing the rolling of the handle, all of said objects being accomplished by the construction, combination and arrangement of parts all as 20 hereinafter set forth, described and claimed.

In the accompanying drawings:

Figure 1 represents a view, partly in elevation and partly in section, of a razor embodying one form of my invention; and

Figure 2 represents a sectional view on line 2—2 of Figure 1, looking in the direction of the arrows.

Referring now in detail to the drawings, 30 A and B represent the usual blade-clamping members, the member A being formed as usual with an externally screw threaded stem C received in the internally screw threaded bore D of the upper end of the handle 1 35 and being provided with the usual locking or positioning lugs E received in registering holes in the blade, not shown, and in the lower clamp member B.

The construction thus far described is 40 very old and well known, being found in the Gillette type of safety razor in practically universal use for a number of years.

The handle 1 is preferably cylindrical in form and is longitudinally centrally bored 45 from its lower end to a point near the lower end of bore D to form a long cylindrical large diameter chamber 8 to receive the styptic pencil 7, said chamber 8 and bore D being separated by the imperforate wall 2.

50 The lower end portion of the inner face

of the wall of chamber 8 is formed with screw threads 3 to cooperate with the external screw threads 5^a of the ferrule or socket 5 of the lower end plug 4.

Said ferrule or socket 5 is preferably of 55 resilient material, cylindrical in cross section and is slotted or split, as at 6, so as to allow the portions thereof to yield slightly as the end of the styptic pencil 7 is forced into position between them and serving to grip 60 and hold between them said styptic pencil 7 after it has been thus forced into said socket. The exact construction of the socket 5 is not of vital importance, it being merely important that there shall be some 65 means of securing the plug 4 and the styptic pencil 7 together so as to be withdrawn and inserted as one operative part, nor is it important that there shall be screw thread connection between the plug 4 and the handle 1, 70 it sufficing it there be some suitable provision for holding the plug 4 in the handle 1.

That portion of the plug 4 which normally extends below the handle 1 will be angular in cross section and appreciably larger in 75 cross section than the handle 1, as well illustrated in Fig. 2, to effectually prevent the rolling of the handle 1 when separated from the clamp members A and B.

The handle 1, plug 4 and its socket or 80 ferrule 5 may all be of any suitable metal, preferably such as will not be corroded by, or set up a chemical reaction with, the styptic pencil or chemical elements thereof, or 85 may be of hard rubber, bakelite or any suitable metal, metal-alloy, or any composition suitable to the purpose, and if a composition such as hard rubber or bakelite is used internally screw threaded metal ferrules may be anchored in the bore D to engage the 90 external screw thread of the stem C; and likewise, if desired, a similar internally screw threaded metal ferrule may be anchored in the lower part of the handle 1 to similarly receive the external screw thread of 95 the 5^a plug 4 of the present embodiment, if desired.

Having thus described my invention, what I claim as new and desire to secure by Letters Patent is:

A safety razor handle having an internally screw threaded bore in its upper end, a large bore forming a chamber extending from its lower end to a point adjacent said upper bore, and the lower portion of said handle being internally screw threaded in said chamber, in combination with a plug having a portion normally extending beyond the lower end of said handle and angular in cross section and appreciably larger in cross section than all portions of said handle, formed with an externally screw threaded portion immediately next above said angular portion to engage in the threads in the lower portion of said handle to close the said chamber and maintain said plug in normal position in said handle, and provided with a resilient split annularly extending ferrule, and a styptic pencil having its lower end forced into, and gripped by, said ferrule to be insertable and withdrawable with said plug as a single operative part in and from said handle wherein it is normally received in said chamber.

In testimony whereof, I have signed my name to this specification at Washington, D. C., this 16th day of February 1929.

MARTIN C. DELLINGER.
